UNITED STATES PATENT OFFICE.

HERMANN LANGE AND KONSTANTIN METTE, OF PETROGRAD, RUSSIA.

MANUFACTURE OF HORSESHOES.

1,246,440.

Specification of Letters Patent. Patented Nov. 13, 1917.

Application filed August 25, 1914, Serial No. 858,535. Renewed October 6, 1917. Serial No. 195,207.

To all whom it may concern:

Be it known that we, HERMANN LANGE, a subject of the Emperor of Germany, and KONSTANTIN METTE, a subject of the Emperor of Russia, both residing at Wass. Ostrow, 17 Linie No. 52, Petrograd, Russia, have invented certain new and useful Improvements in the Manufacture of Horseshoes; and we do hereby declare the following to be a full, clear, and exact description of the invention, such as will enable others skilled in the art to which it appertains to make and use the same.

This invention relates to the manufacture of horse-shoes, and has for its object to provide the novel method of making the same, hereinafter described.

The improved method consists in first producing a bar provided with a central longitudinal rib and a longitudinal rib disposed at either side of the central longitudinal rib, and then cutting the bar transversely into blanks from which the shoes are formed by bending the blanks to bring the heel calk 20 formed at one end of the blank by the transverse cutting of the rib at one side of the bar into proper relation with the heel calk similarly formed at the other end of the blank. During the bending operation of the 30 blank, the ends thereof are preferably attenuated or drawn out to produce a taper at the heel extremities of the shoe.

It has heretofore been proposed to manufacture horse-shoes by rolling out bar-iron 35 longitudinally into the desired E-shaped profile by means of specially toothed rollers. This method, however, is unsatisfactory, in that the calk projections or the like cannot be rolled to sufficient height, and, owing to 40 the nature of the rolling operation, the side faces of the projections do not extend at right angles to the face of the bar. As these projections easily stick and cling in the recesses in the rollers, special ejecting devices 45 have to be arranged at this point on the rollers.

In the present improved method, these defects are obviated by the use of cylindrical rollers formed with smooth annular 50 grooves. By means of such rollers, a flat bar with longitudinal ribs or projections is rolled out, so that the use of ejecting devices on the rollers is not necessary. The ribs can be rolled out of adequate height 55 and with side faces disposed at right angles to the face of the bar.

The invention is illustrated in the accompanying drawings, in which:

Figure 1 is a front elevation, partly in section, of the apparatus for rolling the longitudinal ribs on the bar; 60

Fig. 2 is a broken perspective view of the bar, as it appears when discharged from the apparatus, shown in Fig. 1;

Fig. 3 is a perspective view of a horse-shoe blank cut transversely from the bar, as indicated in dotted lines in Fig. 2; 65

Fig. 4 is a perspective view of the horse-shoe blank after being subjected to a forging operation, the operation being performed by suitable means, such as diagrammatically illustrated in the same figure; 70

Fig. 5 is a plan view, partly in section, of one form of machine which may be used for bending the cut blanks. 75

A flat bar of iron or other material, from which the horse-shoes are to be made, is first produced by passing the iron through a pair of cylindrical rollers *a* and *b* suitably mounted in an appropriate supporting structure *c*, and one of which is provided with annular recesses *d*, *d'* and *d''*, while the other is provided with a single annular recess *e*. The extremities of the roller provided with the three recesses *d*, *d'* and *d''* are of such diameter that they will contact with the other roller, as shown at *f*, thereby producing a confined pass between the rollers, the annular recesses being so formed as to produce the longitudinal ribs on the bar as it enters the pass, as clearly shown in Fig. 2. 80

The shoe blanks are then cut from the longitudinal bar, as indicated by the dotted lines in Fig. 2, the cut blank being indicated at *g*, in Fig. 3. When the blanks are so cut from the bar in Fig. 2, the provision of the longitudinal ribs on the bar results in the projections *h* at the extremities of the blank, which projections subsequently 90 produce the heel-calks of the shoe, as will hereinafter appear, and a central projection *i*, which produces the toe-calk. The longitudinal rib provided on the opposite face of the bar, in Fig. 2, produces, when the blank is cut from the bar, a projection *j*, which is later shaped into the toe-clip, as will also hereinafter appear. 95

The blank shown in Fig. 3 is then subjected to a forging action by any appropriate apparatus, a forging die *k* being represented in Fig. 4 for accomplishing this 100 105 110

purpose. The die *k* is such as to reduce the projections *i* and *j* in width, as clearly shown in Fig. 4.

In Fig. 5, an automatic machine is illustrated for accomplishing the bending operation. In the preferred form, this machine comprises a suitable base or work-table 1, upon which is mounted the counter-die 2. The projection 3 is preferably hingedly associated with the die 2, as shown at 4, to permit the same to be swung to such a position that the feeding and ejection of the blanks will not be interfered with. The blank *g* is placed in the machine with the projection *i* abutting against the member 3. Suitable horizontal guides 5 are provided on the base or bed 1 of the machine, and in these guides are mounted the slidable heads 6 and 7, one being provided at each side of the die 2. Mounted in the slidable heads 6 and 7, are the roller carriers 8 and 9, which are so carried by the slidable heads 6 and 7, that they are movable longitudinally of themselves, and transversely of the slidable heads 6 and 7. This may be accomplished by mounting the roller carriers 8 and 9 in appropriately formed openings passing transversely through the heads 6 and 7. Each roller carrier is provided at its opposite ends with a roller, the outer of which, to wit, that shown at 10, is adapted to coöperate with the removable cam-plates 11. The inner rollers 12 are adapted to co-operate with the shoe blank and to bend the same around the die 2. Each slidable head 6 and 7 is also provided with a recessed or cut-out portion 12', adapted to receive the extremities of the shoe blank. A third slidable head 13 is mounted between the heads 6 and 7 on the guides 14 and removably carries the pressing die 14.

The three heads 6, 7 and 13 are preferably actuated by means of the worm shafts 15 and 16, those shown at 15 being associated with the heads 6 and 7, and that shown at 16 being associated with the head 13. These worm shafts are suitably mounted in the bed or base of the machine and engage appropriate depending portions of the slidable heads, so that a rotary movement of the worm shafts results in a sliding movement of the heads on the guides 5 and 14. Each worm shaft is provided at its extremity with a beveled gear 17, which meshes with two beveled gears 18, one being disposed at either side of the gear 17. The gears 18 are mounted loose upon a driving shaft 19, and are adapted to be connected therewith for rotation thereby, by a suitable clutch mechanism consisting of a sleeve 20 disposed between the two beveled gears 18 of each set, and provided at its opposite faces with clutch teeth adapted to engage coöoperating teeth provided on the adjacent faces of the beveled gears 18. The sleeves

20 are keyed to the shaft 19, and when in one extreme position, are adapted to drive one of the beveled gears 18, and when in the other extreme position, are adapted to drive the other beveled gear 18. In the central position of the sleeves 20, both beveled gears 18 of each set are adapted to remain idle. It is obvious that the direction of rotation of the beveled gear 17 is dependent upon which beveled gear 18 is operatively connected therewith, and when the sleeves 20 are in one extreme position, the sliding heads 6, 7 and 13 will be moved in one direction, and when said sleeves are in the other extreme position, said sliding heads 20 will be moved in the opposite direction. The clutch sleeves 20 are preferably automatically shifted by mechanism not shown in the drawing.

The shaft 19 is preferably driven by a pulley 21, one section of which is mounted loosely upon the shaft 19, and the other of which is fixed thereto, so that by shifting a driving belt thereon, the machine may be started and stopped in the well-known manner.

The operation of the machine is as follows:

After the shoe blank is placed in the position shown in Fig. 10, the clutch sleeves 20 are shifted to connect one or the other of the beveled gears 18 with the driving shaft 19, thereby producing the rotation of the central beveled gears 17 in the proper direction. This results in a forward movement of the slidable heads 6, 7 and 13, the heads 6 and 7 of which start bending the shoe blank *g* around the die 2. The inner rollers 12, by coming into contact with the blank *g*, reduces friction, and prevents injury to the blank, besides pressing all parts of the shoe blank near the toe-portion thereof into engagement with the die 2, in an obvious manner. The die 14 presses the blank firmly against the counter-die 2. The slidable heads 6 and 7, in advancing, cause the roller carriers 8 and 9 to be moved longitudinally of themselves and transversely of the heads 6 and 7 by the cam-plates 11. The longitudinal movement of the roller carriers 8 and 9 by the cam-plates causes each roller 12 to travel in a path almost parallel with the adjacent face of the die 2. The cam face of each cam-plate is so constructed, however, that the inner roller 12 of each roller carrier will gradually approach the die 2, as the heads 6 and 7 near the end of their stroke, thereby producing the attenuating or drawing out action mentioned in the beginning of the specification.

The clutch sleeves 20 then reverse the direction of rotation of the beveled gears 17, and cause the slidable heads 6, 7 and 13 to return to their initial positions. The projection 3 of the die 2 may then be swung to

such a position that it will not interfere with the discharge of the completed shoe from the machine. A new blank is fed to the machine while the projection 3 is in its 5 shifted position, and when said projection 3 is returned to its normal position, shown in the drawings, all is in readiness for a repetition of the cycle of operations, hereinbefore described.

10 What we claim is:—

1. The method of making horse-shoes, which consists in taking a bar having a central longitudinal rib and a longitudinal rib at each side of the bar and cutting the bar 15 transversely into blanks having projections resulting from the transverse cutting of said ribs, and then bending the cut blanks to the desired horse-shoe shape in a plane normal to said projections.

20 2. The method of making horse-shoes, which consists in rolling a flat bar with a longitudinal central rib and a longitudinal

rib disposed at each side of the bar, cutting the bar transversely to form blanks having projections resulting from the transverse 25 cutting of said ribs, and then bending the cut blanks to the desired horse-shoe shape in a plane normal to said projections.

3. The method of making horse-shoes, which consists in rolling a flat bar with a 30 longitudinal central rib and a longitudinal rib disposed at each side of the bar, then cutting the bar at right angles to its longitudinal axis to form blanks, and bending the cut blanks into the desired horse-shoe 35 shape.

In testimony whereof we affix our signatures, in presence of two witnesses.

HERMANN LANGE.
KONSTANTIN METTE.
